UNITED STATES PATENT OFFICE

HARRY E. CAMPBELL, OF BALTIMORE, MARYLAND, ASSIGNOR TO CAMPBELL METAL WINDOW CORPORATION, OF BALTIMORE, MARYLAND, A CORPORATION OF MARYLAND

SASH LIFT

Application filed June 18, 1927, Serial No. 199,690. Renewed October 24, 1929.

The present tendency in window design is to make windows larger than was formerly the custom. This combined with the fact that windows are frequently made of metal and are provided with plate glass, makes them very heavy so that even if friction is reduced to a minimum and the window is accurately counter-weighted, there is a large moment of inertia that must be overcome in 5 starting to move a sash. This is particularly important in connection with the lower sash which is the one ordinarily opened.

The present invention relates to an arrangement of sash lifts which can be made very inexpensively and which will apply leverage to start the lower sash in motion. The arrangement comprises a pair of plates having a portion bent over at the top to form a projection, each of which plates is 10 attached to the lift rail by pivot about in line with one end of the projecting portion. An extension for each plate is provided that goes beyond its pivot, and stops are 15 arranged to limit the movement of the plate about the pivot. The two pivots are both positioned toward the center of the sash and the plates extend down so that their bottom edges contact with the sill. When one starts to lift the sash in the usual manner, the 20 plates will turn about the pivots and the projections will press against the sill exerting leverage to start the sash in motion. The stops should limit the movement of the plates to approximately 30°, and certainly 25 to less than 45°, and inasmuch as the operator normally is above the window sill, it will be found that the projections are then substantially perpendicular to the line of force extending through the operator's arms so that the sash can be very easily continued 30 in its movement. In order to lower the sash, a stop is provided which will prevent the plate from turning substantially below the position where it is parallel with the sill so that for this movement it will operate in 35 the normal manner.

The operation of the lifts and the manner in which they may be made, can be readily understood by a reference to the accompanying drawings, in which Fig. 1 shows the de-

vice as attached to the face of an ordinary wooden window; Fig. 2 is a section on line 2-2 of Fig. 1, but showing the sill; Fig. 3 is a face view of the entire window on a reduced scale; Fig. 4 is a face view of a preferred form of device as attached to a metal window; Fig. 5 is a section on line 5-5 of Fig. 4 but also showing the sill, and Fig. 6 is a section on line 6-6 of Fig. 4.

While my invention is primarily intended for use with metal windows, its simplest embodiment can best be illustrated in connection with a wooden window, as shown in Figs. 1 and 2. In these figures 2 is a metal plate which may advantageously be made of bronze which is bent over at the top to form a projection 4 and is also preferably bent to form a projection 6 at the bottom. The plate has a cam portion 8 reaching toward the center of the sash (see Fig. 3). The plate is attached to the lift rail 10 by a screw 12 which is positioned near the base of the cam portion 8. The bottom projection 6 is so positioned that when the sash is closed it will rest against the sill 14. Two stop pins 16 and 18 are located in the lift rail 10.

When one starts to open the lower sash the plate 2 will pivot about the screw 12 into the position shown in broken lines in Fig. 1 exerting leverage against the sill 14 causing the sash to start in motion. The upward movement of the plate 2 relative to the lift rail 10 will be limited by the pin 16 so that the projections 4 will be substantially perpendicular to the operator's arms as illustrated in Fig. 3 where the lines of pull are represented by the broken lines 20. As soon as the window is opened to the desired point, plate 2 will drop back into position parallel with the lift rail 10 where it will be held by the pin 18. When the sash is to be lowered, the plate 2 simply remains in this horizontal position.

In Figs. 4, 5 and 6 I show a preferred form of device as applied to a sash and sill construction similar to that shown in my co-pending application Ser. No. 165,526, filed February 3rd, 1927. In these figures 22 is the lift rail of the lower sash and 24 is the sill (see Fig. 5). Attached to the

lift rail 22 is a glass stop 26 bent so that it provides a recess 28. In the recess 28 is attached a support 30 having one end 32 bent around so that it is flush with the inner side of the glass stop 26 and the other end 34 bent in and back on itself to provide a plate parallel with the inner face of the glass stop 26. The support 30 may be held in place in any desired way as by a screw 36. Attached to the end 34 of the support 30 is a plate 38 provided with a top projection 40 and a bottom projection 42. This plate is here shown as having a central portion 44 stamped out for the purposes of ornament. The plate 38 has a cam portion 46 corresponding to the cam portion 8 already described in reference to Figs. 1 and 2. A rivet 48 passes through the plate 38 and the end 34 of support 30. Attached to the back of the plate 38 in any desired way, as by the rivet 50, is a stop angle 52. When the plate 38 is parallel with the lift rail, the stop angle 52 will rest against the bottom of the recess 28 and when the plate 38 has reached its position of maximum pivoting movement as illustrated in broken lines in Fig. 4, the stop angle 52 will contact with the top of recess 28. The operation of this form is exactly the same as that already described in connection with Figs. 1, 2 and 3.

If desired, the type of lift illustrated in Figs. 2, 3 and 4 may be used with a window having a normally flat face on the lift rail, 35 by forming an appropriate recess therein.

What I claim is:

1. A window-frame comprising a sill, a sash, a sash lift pivoted near one of the ends of the lift on the inside of the sash 40 and having a cam portion projecting beyond the pivot point adapted to move downwardly to contact with the sill when the lift is pressed upwardly and stop means for limiting the angular movement of the lift 45 so that it cannot move as much as 45° above the horizontal and cannot move substantially below the horizontal, so that the same may be used to move the window both up and down in the usual manner.
- 50 2. A combination as specified in claim 1 which further includes a second similar lift attached to the sash, both said lifts being attached to the sash so that their cam ends are toward the centre.
- 55 3. A combination as specified in claim 1, in which a recess is formed in the face of the sash back of the sash lift and the stop means are adapted to function in said recess.
4. A window-frame comprising a sill, a 60 sash having a lift rail adapted to close against the sill, two members pivoted to the lift rail approximately in contact with the sill when the sash is closed, pivots connecting such members with the lift rail, inwardly 65 extending portions on said members extend-

ing towards the center of the window from said pivots, cam portions of said members reaching towards the center of the sash adapted to contact with the sill to raise the sash when an upward pressure is exerted on said inwardly extending portions and means for limiting the pivoting movement of such members so that the same may be used for raising the sash and so that the same will not contact with the sash to interfere with closing when used to push the sash down.
